(57) **CLAIM**

The ornamental design for a medical electrode, as shown and described.

DESCRIPTION

FIG. 1 is a perspective view of a medical electrode showing our new design;

FIG. 2 is a top view thereof;

FIG. 3 is a left-side view thereof;

FIG. 4 is a bottom view thereof;

FIG. 5 is a right-side view thereof;

FIG. 6 is a back view thereof; and,

FIG. 7 is a front view thereof.

In FIGS. 1-7, the broken lines are for the purpose of illustrating portions of the medical electrode that are not part of the claimed design.
